CLAIM

The ornamental design for a shoe charm post, as shown and described.

DESCRIPTION

FIG. 1 is an isometric view showing a first embodiment of a shoe charm post according to the present disclosure; FIG. 2 is another isometric view of the shoe charm post shown in FIG. 1; FIG. 3 is a front elevational view of the shoe charm post shown in FIG. 1; FIG. 4 is a right side elevational view of the shoe charm post shown in FIG. 1; FIG. 5 is a rear elevational view of the shoe charm post shown in FIG. 1; FIG. 6 is a left side elevational view of the shoe charm post shown in FIG. 1; FIG. 7 is a top plan view of the shoe charm post shown in FIG. 1; FIG. 8 is a bottom plan view of the shoe charm post shown in FIG. 1; FIG. 9 is an isometric view showing a second embodiment of the shoe charm post according to the present disclosure; FIG. 10 is another isometric view of the shoe charm post shown in FIG. 9; FIG. 11 is a front side elevational view of the shoe charm post shown in FIG. 9; FIG. 12 is a right side elevational view of the shoe charm post shown in FIG. 9; FIG. 13 is a rear elevational view of the shoe charm post shown in FIG. 9; FIG. 14 is a left side elevational view of the shoe charm post shown in FIG. 9; FIG. 15 is a top plan view of the shoe charm post shown in FIG. 9; FIG. 16 is a bottom plan view of the shoe charm post shown in FIG. 9; and, FIG. 17 is an isometric view of the first embodiment of the shoe charm post affixed to a shoe in an upper position and the second embodiment of the shoe charm post affixed to the same shoe in a lower position near the toe box. The evenly spaced broken lines shown in FIGS. 1-17 depict portions of the shoe charm post that form no part of the claimed design. The dash-dot-dash broken lines shown in FIG. 17 depict environment and form no part of the claimed design.
